UNITED STATES PATENT OFFICE.

ROBERT CARL RAHM, OF WYOMISSING, PENNSYLVANIA, ASSIGNOR TO TEXTILE MACHINE WORKS, OF READING, PENNSYLVANIA, A CORPORATION OF PENNSYLVANIA.

DUPLEX BRAIDER.

1,118,680.

Specification of Letters Patent. Patented Nov. 24, 1914.

Application filed May 2, 1914. Serial No. 835,824.

To all whom it may concern:

Be it known that I, ROBERT CARL RAHM, a citizen of the United States, residing at Wyomissing, in the county of Berks and State 5 of Pennsylvania, have invented certain new and useful Improvements in Duplex Braiders, of which the following is a specification.

My invention consists of an improved tubular braiding machine comprising lower-deck and upper-deck braiders having coöperating carrier courses, as fully described in connection with the accompanying drawings and the novel features of which are specifically pointed out in the claims.

15 Figure 1 is a front elevation of my improved machine, indicating the essential features thereof. Fig. 2 is a similar end elevation. Figs. 3 and 4 are plan views of the upper and lower deck respectively. Fig. 5 20 is a diagrammatic view indicating the co-operative arrangement of the several courses and the character of the product produced.

The lower-deck braider is provided, as shown, with separate circular courses, 2 and 25 2^a respectively, formed as usual in the upper plate 3 thereof; and with separate series of carriers, 4 and 4^a respectively (Fig. 1), which are operated by carrier gears arranged as usual between the upper plate 3 30 and lower plate 5. A core-way, 6 or 6^a, is provided at the center of each course; through which may be fed a core wire, 7 or 7^a (Fig. 5), upon which the carrier threads of the separate courses are brought together at 35 braiding points 8 or 8^a.

The upper-deck braider, which is mounted upon standards 10 on the lower braider, is similarly constructed, but provided only with a single carrier course, 11, having its 40 center midway between the lower-deck courses; the combined products of the lower braider being passed thereto as hereinafter described. The carrier drive gears of the upper-deck course 11, are driven jointly with 45 those of the lower-deck courses as shown, through a vertical shaft 15 carrying a gear 16, and through an idler gear 17 in mesh with the series of carrier gears; and this idler gear is adjustably mounted in a slot 18 50 of the plate so that the size of the gear 17 may be adapted to produce any desired speed of the upper-deck carriers relative to those of the lower courses though all are driven from the belt wheel 19.

55 As indicated in Fig. 5 the separate core

wires 7, 7^a are covered by the braiding of the two lower-deck carrier courses, and are carried upward through the guide tubes 27, 27^a and jointly covered by the braiding of the single upper carrier course. The final 60 product is carried over the take-off pulley 20 to a take-off drum (not shown), which latter is driven in coöperation with all the carriers as indicated; the belt wheel 21 for said drum being fixed to the transverse shaft 65 22 which is rotated with the carrier gears through the vertical worm shaft 23 and gear wheels 24, 25, and 26. Converging guide-tubes 27, 27^a, are provided for the separate 70 braidings of the lower deck carrier courses; these being carried upon a suitably fixed cross-bar 28 having separate braiding-point passage ways 29, 29^a, for said braidings, and the guide-tubes 27, 27^a, passing through the plates of the upper-deck braider and converging to a point below the fixed braiding-point guide 30 of the latter.

75 It will be seen that the take-off drive wheel 20 is driven at a fixed speed relative to the carriers of the lower braiding courses, 80 while the speed of the carriers of the upper-deck course may be varied so as to provide for varying the closeness of the covering braiding formed by the upper-deck carrier course independently of the fixed relation of the latter to the take-off and lower-deck carrier courses. The several braidings are simultaneously formed and combined to provide a compound product suitable for various purposes.

90 What I claim is:

1. A duplex tubular braiding machine made up of a lower-deck braider comprising a plurality of circular carrier courses having different braiding centers, a coöperating upper-deck braider having a single braiding center, and product guiding means, substantially as set forth.

95 2. A duplex tubular braiding machine made up of a lower-deck braider comprising a plurality of circular carrier courses having separate braiding centers and core-ways, a coöperating upper-deck braider having a single braiding center, and product-guiding means, substantially as set forth.

100 3. A duplex tubular braiding machine made up of a lower-deck braider comprising a plurality of circular carrier courses having separate braiding centers, a coöperating upper-deck braider having a single braiding 105

center, product-guiding means, and drive mechanism adapted to operate the several series of carriers jointly and comprising means for varying the speed of the upper-deck carriers relative to the lower.

4. A duplex tubular braiding machine made up of a lower-deck braider comprising a plurality of circular carrier courses having different braiding centers, a co-operating upper-deck braider having a single braiding center and a take-off mechanism, product-guiding means, and drive mechanism adapted to operate the take-off and the several series of carriers jointly and comprising means for varying the speed of the upper-deck carriers relative to the lower.

5. A duplex tubular braiding machine made up of a lower-deck braider comprising a plurality of circular carrier courses, a co-operating upper-deck braider having a single circular carrier course, and a product guide-mechanism comprising a braiding-point cross-bar for the lower-deck braider having converging guide-tubes supported thereon. 20 25

In testimony whereof I affix my signature in presence of two witnesses.

ROBERT CARL RAHM.
